(57) **CLAIM**

The ornamental design for a sheet identification sensor, as shown and described.

DESCRIPTION

FIG. 1 is a perspective view of the rear, left, and bottom sides of a sheet identification sensor showing our new design;

FIG. 2 is a perspective view of the rear, right, and top sides thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of a part 9-9.

The broken lines shown represent unclaimed subject matter of the sheet identification sensor and form no part of the claimed design.
